Primary Examiner — Kevin K Rudzinski*Assistant Examiner* — Paul D Bohannon(74) *Attorney, Agent, or Firm* — RatnerPrestia(57) **CLAIM**

The ornamental design for a vehicle seat, as shown and described.

DESCRIPTION

FIG. 1 is a front and right side perspective view of a vehicle seat;

FIG. 2 is a rear and right side perspective view thereof;

FIG. 3 is a front elevation view thereof;

FIG. 4 is a rear elevation view thereof;

FIG. 5 is an elevation view thereof from the left side; and,

FIG. 6 is an elevation view thereof from the right side.
The broken line showing of the vehicle seat is for the
purpose of illustrating portions of the vehicle seat and forms
no part of the claimed design.**1 Claim, 6 Drawing Sheets**(56)
